DESIGN FOR MARKSMANSHIP APPARATUS

Edwin E. Fairchild, Los Angeles, Calif.

Application December 3, 1941, Serial No. 104,446

Term of patent 3½ years

To all whom it may concern:

Be it known that I, Edwin E. Fairchild, a citizen of the United States, residing in Los Angeles, in the county of Los Angeles, and State of California, have invented a new, original, and ornamental Design for Marksmanship Apparatus, of which the following is a specification, reference being had to the accompanying drawing, forming part thereof.

Figure 1 is a front elevational view of a marksmanship apparatus showing my new design.

Figure 2 is a side elevational view of the marks-

manship apparatus, a portion of the wall of the cabinet thereof being broken away.

Figure 3 is an elevational view of the back of the marksmanship apparatus.

Figure 4 is a top plan view of the marksmanship apparatus.

Figure 5 is an enlarged front view of the upper portion of the marksmanship apparatus.

I claim:

The ornamental design for a marksmanship apparatus, as shown.

EDWIN E. FAIRCHILD.
